THREADLESS ELECTRICAL COUPLING

Stephen Sanders, 181 Circle Drive, Plandome, N.Y.

Filed Jan. 16, 1964, Ser. No. 78,223

Term of patent 14 years

(Cl. D26—1)

Fig. 1.

Fig. 2.

Fig. 3.

Fig. 4.

Fig. 5.

FIG. 1 is a perspective view of a threadless electrical coupling showing my new design,
FIG. 2 is a top view of the coupling,

FIG. 3 is a view of the large end of the coupling,
FIG. 4 is a side view, and

FIG. 5 is a view of the small end of the coupling.

I claim:

The ornamental design for a threadless electrical coupling, as shown.
